(57) **CLAIM**

We claim the ornamental design for a clamping bar, as shown and described.

DESCRIPTION

FIG. 1 is a right-side perspective view of a clamping bar in accordance with the new design.

FIG. 2 is a left-side perspective view thereof.

FIG. 3 is a right-side view thereof.

FIG. 4 is a left-side view thereof.

FIG. 5 is a top perspective view thereof.

FIG. 6 is a top view thereof.

FIG. 7 is a bottom view thereof.

FIG. 8 is a front view thereof; and,

FIG. 9 is a rear view thereof.

The ornamental design which is claimed is shown in solid lines in the drawings. Broken lines, if present in the drawings, are for illustrative purposes only and form no part of the claimed design.

1 Claim, 5 Drawing Sheets
